[57] CLAIM

The ornamental design for a baby car seat bag, as shown and described.

DESCRIPTION

FIG. 1 is a perspective view of a baby car seat bag showing my new design;

FIG. 2 is a front elevational view;

FIG. 3 is a side elevational view;

FIG. 4 is a bottom plan view thereof;

FIG. 5 is a side elevational view of the bag as in use on a baby car seat, the dotted lines being for illustrative purposes only; and

FIG. 6 is a rear elevational view thereof.
